UNITED STATES PATENT OFFICE.

HERBERT F. MILLER, JR., OF WILLIAMSPORT, PENNSYLVANIA.

REGENERATOR-CHAMBER.

1,173,297.

Specification of Letters Patent. Patented Feb. 29, 1916.

Application filed October 28, 1913. Serial No. 797,727.

To all whom it may concern:

Be it known that I, HERBERT F. MILLER, Jr., a citizen of the United States, residing at Williamsport, in the county of Lycoming and State of Pennsylvania, have invented certain new and useful Improvements in Regenerator-Chambers, of which the following is a specification, reference being had therein to the accompanying drawing.

- 10 My invention relates to that type of regenerators in which the products of combustion from a furnace or hearth are utilized to heat the incoming air or gaseous fuel, or both the air and fuel, and the invention is 15 more especially adapted to that class of regenerators wherein checker-work formed of fire brick, tiles and the like, is employed, which, becoming highly heated by the outgoing passage of the products of combustion 20 therethrough, will impart this heat to the incoming gaseous fuel and air flowing through the checker-work. In the use of regenerators of this type, the chief causes of deterioration are the deposit of dust and dirt 25 in the checker-work openings, and the slagging of the brick, this latter action being caused by the chemical action of the deposited dust in the form of iron oxid in the presence of high heat. The deposit of dust 30 and dirt in the checker-work openings is due mainly to the passage of the products of combustion therethrough in a downward direction, and to the inability to readily clean the checker-work without removing the 35 same, which latter operation is objectionable in respect to the liability of spalling the brick by handling.

It is the aim of my invention to overcome these objections and to produce a construction of regenerator in which the liability of deposit of dust or dirt will be reduced to a minimum, and in which the checker-work may be readily cleaned without danger of injury even while the furnace is in operation.

With these ends in view my invention consists in arranging the checker-work in a chamber forming in effect an enlarged portion of the flue leading from the downtake 50 to the stack or chimney, so that the products of combustion will pursue substantially a straight path in their passage from the

downtake to the stack. The checker-work is so disposed in this chamber, that air spaces will be left at opposite ends, which will 55 cause the products of combustion to slow down in their flow and deposit the suspended dust on the floors of the air spaces, from which these deposits may be removed through doors entering the air spaces from 60 the outside. At certain periods in the operation of the furnace, say at the end of the week after the last heat is out, the cold air may be turned into the checker work that is to be cleaned, and after the temperature of 65 the same has in this way been sufficiently reduced, a workman may enter, and by means of compressed air or steam, the checker-work openings may be freed of such deposits as may have occurred.

70 In the accompanying drawings I have shown my invention embodied in the form which at the present time I deem most suitable for the results to be attained; but it will be understood that the construction may be 75 modified and changed in many particulars and details without departing from the limits of my invention; and further it will be understood that the invention is not limited to any particular form or construction 80 of the parts except in so far as such limitations are specified in the claims.

In the accompanying drawings: Figure 1 is a diagrammatic plan view of an open hearth of a regenerative furnace showing 85 my invention embodied therein. Fig. 2 is a side elevation of the same partly in section. Fig. 3 is a plan view on an enlarged scale of one of the regenerator chambers partly in section. Fig. 4 is an elevation of the same 90 partly in section. Fig. 5 is a section taken on the line 5—5 of Fig. 3.

Referring to the drawings: I have shown my invention applied, by way of example, in connection with an open hearth furnace 1, 95 connected at each end with two regenerator chambers, 2 and 3, for air and gaseous fuel respectively, the said chambers communicating at their ends distant from the furnace, with a chimney or stack 4, by means 100 of horizontal flues 5, 5^a, leading from the chambers 2, and flues 6 and 6^a, leading from the chambers 3. At their opposite ends the chambers communicate with vertical flues 8

and 9 (serving as downtime or uptake flues according to the direction of flow of the currents) leading respectively from the opposite ends of the furnace, the communication 5 of chamber 2 with said flues being by means of horizontal flues 10, 10, and the communication of chamber 3 with said flues being by means of horizontal flues 11, 11. At their opposite ends chambers 3 are also connected 10 by means of gas sewers 12, 12, with a source of gaseous fuel supply, in the present instance a gas producer furnace 13. The several flues, 5, 5^a, 6, 6^a, and the gas sewers, are provided as usual with regulating valves 15 by means of which the passage of the currents of air, gaseous fuel and products of combustion through the several flues and chambers may be controlled.

The regenerator chambers connecting the 20 horizontal flues leading from the furnace to the stack, form in effect enlarged continuations of said flues, and disposed in each chamber is a checker-work 15 which terminates at its ends a suitable distance from the 25 ends of the chamber, thereby leaving air spaces 16, 16, at each end of the chamber, the sides of which spaces converge at an easy angle as the flue ends are approached. As 30 a result of this construction and disposition of the parts, the products of combustion are not compelled to pass downwardly through the checker-work openings in finding their exit to the stack, but they will pursue a horizontal straight and direct course from the 35 lower ends of the downtime to the flues leading to the stack, the flowing currents before entering the checker-work openings being slowed up in the enlarged space, and the dust and dirt held in suspension being deposited 40 on the floor of said space. The deposits may be conveniently removed through a door 17, in the side of the space, which door of course will be sealed up when not in use. The checker-work is preferably built 45 on the floor of the chamber, thereby avoiding the use of the usual unstable supporting tiles and rider walls, and occupying the entire cross-sectional area of the chamber with their ends extending clearly there-across, 50 there will be a uniform distribution of air and waste gases through the chamber, due to the opportunity afforded in the air space for the currents to spread over the entire cross-section of the checker-work. As a result 55 there will be increased efficiency in the operation of the furnace, and a minimum deposit of dust and dirt on the bricks of the checker-work nearest the hearth. Also, by reason of the disposition of the checker-work as described, both ends of the same are readily 60 accessible from the air chambers for cleaning purposes, and such deposits in the openings as may occur, may be removed by workmen in the air spaces by the use of com-

pressed air or steam and without the necessity of touching or handling the bricks, it of course being necessary to first reduce the temperature of the checker-work sufficiently to permit workmen to occupy the air spaces.

While in the drawings I have disclosed a 70 checker-work structure formed of fire brick, and while in the specification I have referred to this structure as a "checker-work," and further while the structure is also referred to by such distinction in the claims, it will be 75 understood that the expression is intended to embrace not only checker-work structures *per se* as made up of fire bricks, but all equivalent devices and structures having the capability of absorbing heat from the products of combustion, and imparting the same to the incoming air or gaseous fuel, provided these structures are adapted for operation and use under the conditions above mentioned.

Having thus described my invention what I claim is:

1. In combination with a furnace, an upright flue communicating with the same, a horizontal flue leading from the lower end 90 of the upright flue, a regenerator chamber of relatively greater cross sectional area than that of the flue, said regenerator chamber being connected with the flue and forming a horizontal enlarged continuation of 95 the same, whereby the gaseous currents will be slowed up as they enter the enlarged regenerator chamber, and the dust and dirt held in suspension will be deposited on the floor of said chamber, a horizontal flue leading from the opposite end of the regenerator chamber, and a checkerwork in said regenerator chamber extending throughout the cross sectional area of the same, said checkerwork terminating at its ends inward of the ends of 100 the chamber, thereby leaving cleaning spaces in the chamber at opposite ends of the checkerwork in which cleaning spaces the entire transverse area of the ends of the checkerwork are respectively exposed.

2. In combination with a furnace, an upright flue communicating with the same, a horizontal flue leading from the lower end 115 of the upright flue, a regenerator chamber of relatively greater cross sectional area than that of the flue, said regenerator chamber being connected with the flue and forming a horizontal enlarged continuation of the same, whereby the gaseous currents will be slowed up as they enter the enlarged regenerator chamber, and the dust and dirt held in suspension will be deposited on the floor of said chamber, a horizontal flue leading from the opposite end of the regenerator chamber, and a checkerwork in said regenerator chamber extending throughout the cross sectional area of the same, said checkerwork terminating at its ends inward of the 120

110

115

ends of the chamber, thereby leaving cleaning spaces in the chamber at opposite ends of the checkerwork in which cleaning spaces the entire transverse area of the ends of the 5 checkerwork are respectively exposed, the side walls of said cleaning spaces sloping inwardly toward the respective flues.

In testimony whereof I have affixed my signature in presence of two witnesses.

HERBERT F. MILLER, JR.
